SUCTION CLEANER

Kenneth P. Schory, Bensenville, Ill., assignor to
The P. A. Geier Company, Cleveland, Ohio, a
corporation of Ohio

Application January 17, 1949, Serial No. 271

Term of patent 7 years

(Cl. D9—2)

To all whom it may concern:

Be it known that I, Kenneth P. Schory, a citizen of the United States, residing at Bensenville, in the county of Du Page and State of Illinois, have invented a new, original, and ornamental Design for a Suction Cleaner, of which the following is a specification, reference being had to the accompanying drawing, forming part thereof.

Figure 1 is a perspective view of a suction cleaner showing my new design;

Figure 2 is a top plan view thereof;

Figure 3 is a side elevational view thereof; and

Figure 4 is a front elevational view thereof looking in the direction of the arrows 4—4, Figure 3.

I claim:

The ornamental design for a suction cleaner, substantially as shown.

KENNETH P. SCHORY.
